United States Patent Office

Des. 231,757
Patented June 11, 1974

231,757

CHAIR

Siegbert Golzer, Saarbrücken, Germany, assignor to Mauser Kommanditgesellschaft, Cologne, Germany

Filed June 6, 1972, Ser. No. 260,345

Claims priority, application Germany Jan. 17, 1972

Term of patent 14 years

Int. Cl. D6—01

U.S. Cl. D6—56

FIG. 2

FIG. 1

FIG. 4

FIG. 3

FIG. 1 is a front view of the chair showing my new design;

FIG. 2 is a perspective side view of this chair;

FIG. 3 is a perspective front view of the chair; and FIG. 4 is a perspective rear view of the chair.

The appearance of the chair not shown in the drawing is identical with the appearance of the side shown in FIG. 2 of the drawing.

I claim:

The ornamental design for a chair, substantially as shown and described.
